UNITED STATES PATENT OFFICE

LEONARD PAGET, OF TRENTON, NEW JERSEY, ASSIGNOR TO THE MACRAEON STORAGE BATTERY COMPANY, OF NEW YORK, N. Y.

ELECTRIC-LIGHT REGULATOR.

SPECIFICATION forming part of Letters Patent No. 393,574, dated November 27, 1883.

Application filed May 23, 1883. Serial No. 275,306. (No model.)

To all whom it may concern:

Be it known that I, LEONARD PAGET, a citizen of the United States, residing at Trenton, in the county of Mercer and State of New Jersey, have invented a new and useful Improvement 5 in Electric-Light Regulators, of which the following is a specification.

My invention relates to improvements in arc-light regulators in which the feed of the 10 carbons or electrodes is regulated or governed by thermal effects and adapts the lamp for use with either direct or alternating current generators of electricity.

It is well known by electricians that arc 15 lamps governed by electro-magnetic regulators, or, in fact, any regulator in which the carbons are in contact when no current is flowing over the circuit, cannot be advantageously used on circuits supplied by secondary batteries, for the reason that the low-resistance 20 path offered the current through the carbons creates such intense heat at the point of contact that they become fused together before they can separate, thus preventing the operation 25 of the lamp.

It is the especial object of my invention to overcome this objectionable feature, and also to provide an arc-light regulator which shall be equally well adapted for use with direct 30 and alternating current generators. I accomplish these objects through the agency of a thermal regulator which holds the electrodes normally out of contact when no current is on the line and allows them to come momentarily 35 into contact after the current has been set up, and then withdraws them, thereby establishing the arc. This regulator consists of a thermal conductor attached to the electrode-carriers and constitutes a high-resistance shunt 40 to the normally-open circuit at the electrode-points. With such a regulator I am enabled to establish the arc in every instance and to avoid the objectionable feature referred to above.

45 My invention will be better understood by reference to the accompanying drawings, in which—

Figure 1 illustrates a side elevation of a regulator in which only one carbon electrode is fed 50 forward, and Fig. 2 a modified form adapted to feed both electrodes simultaneously.

Referring to the drawings in detail, A is an insulating support or base which carries or supports the several parts of the regulator.

B is a metallic bar attached to the base A 55 on the left. At its upper end is a binding-post, P, connected to the plus-pole of the generator in the usual manner. At the lower end, D, of the bar B is pivoted an arm, G, which carries a hollow carbon-holder, C, in 60 its lower upturned end, M.

B' is a metal bar rigidly secured to the support A on the right-hand side, and having a binding-post, P', at its upper end for connecting it with the minus-pole of the generator. 65 The lower end of this bar B' has an electrode holder and guide, C.

E' E² are the electrodes, the former of carbon and the latter (in Fig. 1) of non-combustible material—iron, copper, or like material; 70 but in Fig. 2 both electrodes are of carbon or the material generally made use of in arc lights.

K is a clutch-lever pivoted to the carbon-carrier C, its lower end being sufficiently long and heavy to hold the carbon from feeding forward under normal conditions. The flat leaf-spring L is adapted to aid the weighted end in firmly gripping the electrode.

P² is a screw adapted to abut against the short arm of the lever K when the arm G tilts 80 to the right.

I is a high-resistance wire of platinum, attached at one end to the upper end of the short arm of lever G by an adjusting-screw, T, and passing thence around pulleys H H H to the 85 upper end of the bar or plate B, to which it is affixed by an adjusting-screw, T', for regulating its length.

The operation is as follows: The battery having been connected to binding posts P P', 90 the current passes by plate B, short arm of lever G, to wire I, and thence by plate B' to line. This heats the high-resistance wire I, thereby expanding it, causing the lower end of lever G to tilt to the right until the upper 95 end of lever K is brought into contact with screw P², thereby releasing the electrode E' and allowing it to slide forward until it touches the opposing electrode E². Immediately the current takes the low-resistance path through 100 the electrodes, and this permits the wire I to cool and hence to contract, thus causing the

electrodes to separate and the arc to be established. This operation is repeated when the arc becomes abnormal.

The modified form shown in Fig. 2 differs 5 from that shown in Fig. 1, in that both carbons or electrodes are fed forward, the arm G on the right and its attachments being a duplication of those shown on the left in Fig. 1, the wire I being connected in this instance to 10 the upper ends of both levers G. I prefer to so adjust the wire that it is heated sufficiently to feed the electrodes at a temperature of from 100° to 200° centigrade, and in practice I find the best temperature to be about 125°, as the 15 wire appears to be more sensitive at that temperature to varying changes of current strength, due to the operation of the lamp.

I am aware that it is not broadly new with 20 me to regulate the feed of arc-light electrodes by means of thermally-actuated devices, and I do not claim such, broadly; but,

Having thus described my invention, what I 25 do claim, and desire to secure by Letters Patent of the United States, is—

1. An arc-light regulator consisting of a 25 high-resistance thermal electrical conductor located in a shunt around the electrodes and connected directly to the carbon-carriers, in combination with clutch mechanism whereby 30 the arc is established and continued, substantially as described.

2. A regulator for arc lamps, consisting of a 30 high-resistance thermal electrical conductor

in a permanently-closed shunt about the electrodes, in combination with pivoted arms carrying the electrodes at their lower ends, the upper ends of said pivoted arms being connected directly to the thermal electrical conductor, while the lower ends are provided with feeding-clutches, substantially as described. 35 40

3. A regulator for arc lamps, consisting of a pivoted carbon-carrying lever having one of its arms attached directly to an expansible conductor shunting the electrodes, in combination with a clutch and a movable electrode 45 borne by the other arm of said lever, and a fixed releasing-stop adapted to act on the releasing-clutch, substantially as described.

4. A thermal regulator consisting of a high-resistance expansible shunt about the electrodes, in combination with a carbon-feeding 50 clutch pivotally attached to the carbon-carrier, and said carbon-carrier being pivoted and attached directly to the shunt, substantially as described.

5. An electric lamp consisting of two gravitating electrodes normally held out of contact by clutches attached directly to the carbon-carrier, in combination with a high-resistance expansible shunt and connections, as described, 55 60 for establishing the arc and feeding the carbons.
